UNITED STATES PATENT OFFICE

CARL J. LINDEGREN, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

LENO JUMPER SADDLE

Application filed August 22, 1931. Serial No. 558,770.

This invention relates to leno or cross weaving looms and it is the general object of the invention to improve the support for the looped link used in the connection of the leno harness frames.

In cross or leno weaving it is customary to give certain of the harness frames either half movements, or full movements, depending upon whether mesh or heading fabric is being woven. When weaving mesh certain harness frames move from low position to mid-position to permit shogging of the needle frame, after which these frames are lowered to cross their warps with those of the needle frame. In some fabrics there is an occasional strip of plain, or non-mesh, fabric, in the weaving of which the aforesaid frames move in the usual manner, that is, from low to high position and return.

Two separate actuators may be employed to give these results, the ordinary harness jack for the full motion when weaving plain, and a half-and-return, or jumper when weaving leno. The connections to the harness frames include hollow or loop links through which the jacks extend and to one end of which are attached the leno or jumper actuators. When the jumper is active the jack is in low position so as not to interfere with the half-and-return motion of the harness frames.

It is an important object of my invention to provide a support or saddle for the link so constructed that it will be held in place on the jack by its own weight. A further object is to form the saddle with a curved upper edge or surface to permit the link to remain in the same position vertically without varying the shed as the jack moves.

Another object of the invention is to provide a readily adjustable saddle movable by hand to the desired notch and arranged to fall into holding or locked position on the jack. In this connection the link is formed with ears one of which will act to hold the

saddle in the selected notch when the jack is operative. In this way any tendency of the saddle to jar loose by the motion of the jack is prevented.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a front elevation of a dobby with my invention applied thereto,

Fig. 2 is a perspective view of the upper end of a dobby harness jack showing my invention held in position in one of the notches of the jack,

Fig. 3 is an enlarged front elevation of the saddle, and

Fig. 4 is a top plan view taken in the direction of arrow 4, Fig. 3.

Referring to the drawing, I have shown the dobby frame 10 having a harness jack 11 pivoted thereto and along the upper right hand edge of which is a series of notches 12. The harness sheave 13 may be properly supported by the loom frame and have extended therearound a harness cord 14. The latter is connected to a hollow or loop link 15 the right hand end of which as shown in Fig. 1 is attached to a strap 16. The upper end of the harness jack passes through the looped link the slot in which is of greater length than the width of the jack.

A sector 17 is pivoted as at 18 and is swung by a train of parts including a toggle link 19. The actuation of the train is through a rod 20 driven by rocker arm 21 of the dobby. The dobby jack 11 may be moved by lever 22 in the usual manner and has an amplitude of motion greater than that of the sector 17.

When leno is being woven the jack will be in a position corresponding to the down po-

sition of the corresponding harness frame and the sector will be effective to give said frame a half movement without disturbing the jack. When it is desired to discontinue 5 leno and start the weaving of some non-leno fabric, the jack will be moved from the full line position shown on Fig. 1 to the dotted line position, thereby giving the harness frame a full or complete movement. It is to 10 be understood that the sector operates merely to raise the warps to mid-position and then, after a lateral shift, lets the warp fall.

The matter thus far described is substantially the same as that shown in the Patent 15 No. 743,675 to which reference may be had for a more complete understanding of the dobby.

My present invention relates more particularly to a guide and a support for link 15, and in carrying my invention into effect I provide 20 a saddle or support having side members or plates 41 and 42 between which extends a rounded notch engaging cross bar 43 and also a weight 44. The latter is at that end of the saddle opposite the cross bar 43 and the 25 slot 45 between the side links receives the jack 11. The upper surfaces of the sides 41 and 42 are curved as at 46, extending downwardly from the cross bar 43 so that the weight 44 lies at a substantial distance below the cross bar. The length of the slot 45 is somewhat greater than the width of that 30 part of the jack extending therethrough, so that the saddle will assume the downwardly inclined position shown in Fig. 1.

When applying the saddle it will be slipped 35 over the upper end of the jack and the cross bar 43 inserted in one of the slots, after which the weighted end is released to fall down and engage the edge 47 of the jack opposite the 40 notch 12. When in this position the center of gravity of the saddle will lie below the cross bar, this relation effectively holding the saddle in position on the jack and preventing dislodgement.

The link differs from that shown in the 45 patent in that it has upper and lower lugs 50 and 51, respectively, which lay on opposite sides of the center line of the link. The lower lug will ordinarily be in alignment 50 with the cross bar 43, so that when the jack is moving to the right as viewed in Fig. 1, a strain will be placed upon the link the effect of which is to cause lug 51 to hold the cross bar in its notch, thus preventing dislodgement 55 of the saddle from the jack while the latter is moving. During the oscillation of the jack 11 the lower edge 52 of the link 15 will roll along the curved upper surface of the saddle and the curvature of said surfaces 60 is such that the link is held in a substantially horizontal position, thus maintaining a uniform shed.

From the foregoing it will be seen that I 65 have provided a simple form of link saddle or support which is held in position by its

own weight on the harness jack. It will also be seen that the saddle has curved surfaces which maintain rolling contact with the link when the harness jack has a harness lifting movement. Furthermore, the vertically extending lugs on the link are provided so that the link may be inserted and still be able to hold the saddle on the correct position on the jack, but preventing the cross bar 43 from becoming dislodged from this notch. When 70 the position of the links 15 is to be changed, it is necessary merely to raise the saddle and move it to the desired notch.

Having thus described my invention it will be seen that changes and modifications may be made therein by those skilled in the art without departing from the spirit and scope of the invention and I do not wish to be limited to the details herein disclosed, but what I claim is:

1. In a leno motion for a loom dobby, a harness jack having notches in one edge thereof, a leno loop surrounding the jack, and a support encircling the jack below the loop and having a part to enter a notch in the jack and having another part opposite the notches weighted to engage the jack and hold the support in position.

2. In a leno motion for a loom dobby, a harness jack having notches in one edge thereof, a leno loop surrounding the jack, and a supporting saddle under the loop and entering one of the notches and held in position on the jack by the weight thereof, the part of the saddle adjacent the loop having an upwardly curved surface to engage the loop with a rolling action as the jack moves the loop.

3. In a leno motion for a loom dobby, a harness jack having notches in one edge thereof, a leno loop surrounding the jack, a saddle support having a part to enter a notch in the jack and having another part to engage the edge of the jack opposite the notches, the weight of the saddle holding the first named part in the said notch.

4. In a leno motion for looms, a harness jack, a leno loop surrounding the jack, and a support held to the jack under the loop and having an upwardly curved surface to have rolling supporting relation with the loop when the latter is moved by the jack.

5. In a leno motion for a loom dobby, a harness jack having notches in one edge thereof, a leno loop surrounding the jack, and a support under the loop having a part to enter one of the notches and having another part to engage the edge of the jack opposite the notches at a point below the first named part, the weight of the support holding the same in position on the jack.

6. In a leno motion for a loom dobby, a harness jack having notches in one edge thereof, a leno loop surrounding the jack, and a support under the loop having a part

to enter one of the notches and having another part to engage the edge of the jack opposite the notches at a point below the first named part, the weight of the support holding the same in position on the jack, said parts being farther apart than the distance between the edges of the jack, whereby raising the second part releases the first part from its notch.

10 In testimony whereof I have hereunto affixed my signature.

CARL J. LINDEGREN.
